United States Patent Office

Des. 212,000
Patented Aug. 20, 1968

212,000

DESK TELEPHONE SET

Ashot Akopovich Partizpanian, Ul. Lenina 8, kv. 6,
Riga, U.S.S.R.

Filed Oct. 11, 1967, Ser. No. 8,949

Term of patent 14 years

(Cl. D26—14)

FIG. 1

FIG. 2

FIG. 3

FIG. 4

FIG. 1 is a perspective view of a desk telephone set, showing my new design;

FIG. 2 is a front perspective thereof, with the handset removed from the telephone base;

FIG. 3 is a side elevation of the telephone base, the handset has been omitted for ease of illustration; and

FIG. 4 is a perspective as seen from the rear of FIG. 1.

I claim:

The ornamental design for a desk telephone set, substantially as shown and described.
